CADDY OR SIMILAR ARTICLE

Norman P. McLeod, 1114 W. St. Andrews Place,
Santa Ana, Calif. 92802

Filed Nov. 7, 1968, Ser. No. 14,344

Term of patent 14 years

Int. Cl. D6—01

U.S. Cl. D33—3

FIG. 1

FIG. 2

FIG. 3

FIG. 4

FIG. 1 is a top plan view of a caddy or similar article, showing my new design;

FIG. 2 is a side elevational view thereof;

FIG. 3 is a front elevational view thereof; and

FIG. 4 is a rear elevational view thereof.

The side not shown is a mirror image of the side shown.

I claim:

The ornamental design for a caddy or similar article, substantially as shown and described.
